UNITED STATES PATENT OFFICE.

BUFORD L. RUCKER, OF PHOENIX, ARIZONA.

SHOE CLEANER.

Application filed June 19, 1925. Serial No. 38,262.

To all whom it may concern:

Be it known that I, BUFORD L. RUCKER, a citizen of the United States, residing at Phoenix, in the county of Maricopa and State of Arizona, have invented certain new and useful Improvements in Shoe Cleaners, of which the following is a specification.

This invention relates to improvements in shoe cleaners and has for its principal object to provide a pair of substantially L-shaped complementary brush heads, means being provided for securing the same together, it being further adapted to be detachably secured on a floor or running board of an automobile, so that a person may clean his shoes, without necessitating the use of his hands.

A still further object is to provide a shoe cleaner of the above mentioned character, which is of such a construction as to enable dirt and mud to be removed from the bottom as well as from the sides of a shoe, when the latter is placed between the complementary brush heads.

25 A still further object is to provide a shoe cleaner of the above mentioned character, which is simple in construction, inexpensive, strong and durable, and further well adapted for the purpose for which it is designed.

30 Other objects and advantages of the invention will become apparent during the course of the following detailed description.

In the accompanying drawing, forming a part of this specification, and in which like reference characters designate corresponding parts throughout the several views:

Figure 1 is an end elevation of my improved shoe cleaner.

Figure 2 is a top plan view of the securing means for the complementary brush head, and

Figure 3 is a front elevation of the shoe cleaner.

In the drawing, wherein for the purpose of illustration is shown the preferred embodiment of my invention, the numerals 1 and 2 designate a pair of opposed brush heads, the same being substantially of L-shaped design. The shorter arm or base 3 of each of the substantially L-shaped brush heads has its upper face curved, as illustrated at 4. Extending inwardly from the inner faces of the longer arms of the L-shaped brush heads are the bristles 5. The free ends of the bristles 55 extend to substantially the same vertical plane of the inner opposed ends of the re-

spective shorter arms or bases of the L-shaped brush heads, as is clearly illustrated in Figure 1. Extending upwardly from the shorter arms or base portions 3 of the brush heads are the vertical bristles 6. These bristles are relatively short and the upper edges of the vertically disposed bristles lie in substantially the same plane.

The securing means for the complementary brush heads comprises a pair of complementary base plates 7 and 8 respectively, the inner opposed ends thereof being hingedly secured together, as illustrated at 9. These base plates are adapted to be secured to the bottom of the base portion of the L-shaped brush heads 1 and 2 respectively, through the medium of the screws 9. In this manner, the brush heads are hingedly secured together. Laterally extending ears 10 are formed on each of the base plates adjacent the inner ends thereof, a similar pair of ears 11 extending laterally from each of the base plates from the opposite sides of the outer ends thereof. The inner pair of opposed laterally extending ears 10 are provided with openings 12, whereby the base plate may be secured to the floor, through the medium of screws or where the shoe cleaner is to be attached to the running board of an automobile, bolts are adapted to extend through the openings provided in the ears 10.

The outermost pairs of opposed laterally extending ears 11 are slotted, as indicated at 13, for engagement with suitable fastening screws 14, which have been previously driven into the floor, and the heads thereof extend upwardly therefrom. It is of course to be understood that when securing the shoe cleaner on the floor, the slotted portions 13 of the ears 11 will be in engagement with the fastening screws 14, before fastening screws 15 may be driven into the floor through the openings 12 provided in the ears 10.

When the shoe cleaner is secured on the floor, as is illustrated in Figure 1, the dirt and mud may be removed from the shoes by moving the foot forwardly and rearwardly between the complementary brush heads, the horizontally disposed bristles 5 being in engagement with the sides as well as a portion of the top of the shoes, while the vertically disposed bristles engage the bottom of the shoe. In this manner, a person may readily clean his shoes, without necessitating the use of his hands.

In order that the shoe cleaner may be cleaned, the same is removed from its stationary engagement with the floor by removing the fastening screws 15 and disengaging the slotted portions of the ears 11 from engagement with the screws 14. The brush heads are then opened, by swinging the same outwardly in opposite directions, so that the base plates 7 and 8, will have their bottom faces abutting each other and thus causing the bristles on each of the brush heads to be disposed out of cooperative relation with respect to the complementary bristles on the brush head. The dirt and dust which collect between the bristles may then be easily removed therefrom.

It will thus be seen that a shoe cleaner has been provided, which will, at all times, be positive and efficient in carrying out the purposes for which it is designed, and will furthermore save considerable time and labor in removing the dirt and mud from a person's shoe.

While I have shown the preferred embodiment of my invention, it is to be understood

that various changes in the size, shape, and arrangement of parts may be resorted to, as do not depart from the spirit of the invention or the scope of the appended claim.

Having thus described my invention, what I claim as new is:

A shoe cleaner comprising a pair of opposed complementary brush heads of substantially L-shaped design, the base portion of each of said L-shaped brush heads having its upper face curved, bristles extending horizontally from the inner opposed faces of the arms of the L-shaped brush heads, additional bristles extending upwardly from the curved upper faces of the base portions of the L-shaped brush heads, securing means for said brush heads, said securing means comprising a pair of base plates secured to the bottom faces of the bases of the brush heads, the inner opposed ends of said base plates being hingedly secured together, said base plates being provided with means for securing the cleaner to a support.

In testimony whereof I affix my signature.

BUFORD L. RUCKER.
